UNITED STATES PATENT OFFICE.

ANTHONY L. WESTGARD, OF NEW YORK, N. Y.

DESIGN FOR AN EMBLEM.

40,734.

Specification for Design.

Patented June 21, 1910.

Application filed April 15, 1910. Serial No. 555,744. Term of patent 7 years.

To all whom it may concern:

Be it known that I, ANTHONY L. WESTGARD, a citizen of the United States, and a resident of the city, county, and State of New York, have invented a new, original, and ornamental Design for Emblems, which design is fully set forth in this specification, reference being had to the annexed drawing, forming part hereof, in which—

2 a rear elevation, and Fig. 3 a side view of the embodiment of my design.

I claim:

The ornamental design for an emblem, as shown.
